UNITED STATES PATENT OFFICE.

SAMUEL D. BUTTERWORTH, OF LANSING, MICHIGAN.

TIE-PRESSING DEVICE.

1,196,515.

Specification of Letters Patent. Patented Aug. 29, 1916.

Application filed November 8, 1915. Serial No. 60,172.

To all whom it may concern:

Be it known that I, SAMUEL D. BUTTERWORTH, a citizen of the United States, residing at Lansing, county of Ingham, State of Michigan, have invented a certain new and useful Improvement in Tie-Pressing Devices, and declare the following to be a full, clear, and exact description of the same, such as will enable others skilled in the art to which it pertains to make and use the same, reference being had to the accompanying drawings, which form a part of this specification.

This invention relates to a portable tie pressing device, comprising a pair of connected wings, each of which is shaped to fit one end of the tie and expand and stretch it.

In the drawings, Figure 1 is a view of the device. Fig. 2 shows the device in use on a tie.

It is a very common fault for ties to become baggy and wrinkled and they should be pressed quite frequently. This, however, is an operation that the average man would not care to perform and unless he has someone to care for his ties they soon get out of order. Another very common fault in a man's four-in-hand tie is the tendency of the wadding in the tie to crumple up and bunch in some one place to the annoyance of the wearer of the tie. These objections I have found can be very simply eliminated by a very simple apparatus such as I have shown in the accompanying drawings.

Fig. 1 shows a pair of tapered flat wings connected by a chain. One of these wings is larger than the other; the large wing is intended to be thrust into the large end of the tie; the small wing is intended to be thrust

into the small end of the tie, as shown in Fig. 2. When the wings are thrust in the ends of the ties and the ties are thrust down over the tapered wings, the wings hold the tie ends in a stretched flat position, as shown in Fig. 2. When allowed to remain this way over night, for instance, the tie is flattened out and substantially pressed as can be done with an iron. If this operation is performed after every time the tie is used, the tie will be kept in very good order and will save the wadding from being bunched. If the tie is made of material that will not be harmed by moisture, sprinkling will help the pressing operation.

The chain serves two purposes. It serves to connect the two wings together to make them handy to handle, and it also pairs the proper two wings together for any particular design of tie. Inasmuch as there may be several sizes of ties and it is more suitable to have different sized wings, it is eminently desirable that these wings be paired together so that the proper members of each pair can always be kept from confusion.

The wings may be made of any suitable metal, such as tin, aluminum or the like.

What I claim is:

A tie pressing device, comprising a pair of tapered wings, one larger than the other, the larger one being designed for stretching the large end of the tie and the smaller wing being designed for stretching the small end of the tie by thrusting the same in the tie ends, and a flexible linear member for connecting the two tapered wings together.

In testimony whereof, I sign this specification.

SAMUEL D. BUTTERWORTH.
